(57) **CLAIM**

The ornamental design for a seat, as shown and described.

DESCRIPTION

FIG. 1 is a front perspective view of a seat showing the new design;

FIG. 2 is a rear perspective view of the seat as shown in FIG. 1;

FIG. 3 is a front view of the seat as shown in FIG. 1;

FIG. 4 is a rear view of the seat as shown in FIG. 1;

FIG. 5 is a side view of the seat as shown in FIG. 1; other side view being a mirror image; and

FIG. 6 is a top view of the seat as shown in FIG. 1;

FIG. 7 is a bottom view of the seat as shown in FIG. 1;

FIG. 8 is a front perspective view of a variation of the design for a seat;

FIG. 9 is a rear perspective view of the seat as shown in FIG. 8;

FIG. 10 is a front view of the seat as shown in FIG. 8;

FIG. 11 is a rear view of the seat as shown in FIG. 8;

FIG. 12 is a side view of the seat as shown in FIG. 8; other side view being a mirror image;

FIG. 13 is a top view of the seat as shown in FIG. 8; and

FIG. 14 is a bottom view of the seat as shown in FIG. 8;

FIG. 15 is a front perspective view of another variation of the design for a seat;

FIG. 16 is a rear perspective view of the seat as shown in FIG. 15;

FIG. 17 is a front view of the seat as shown in FIG. 15;

FIG. 18 is a rear view of the seat as shown in FIG. 15;

FIG. 19 is a side view of the seat as shown in FIG. 15; other side view being a mirror image; and

FIG. 20 is a top view of the seat as shown in FIG. 15; and,

FIG. 21 is a bottom view of the seat as shown in FIG. 15.
